UNITED STATES PATENT OFFICE.

OLE O. KITTELESON, OF ROCK FALLS, ASSIGNOR TO CHARLES H. SALISBURY,
OF DE KALB, ILLINOIS.

WIRE-BARBING MACHINE.

SPECIFICATION forming part of Letters Patent No. 350,982, dated October 19, 1886.

Application filed March 29, 1886. Serial No. 197,074. (No model.)

To all whom it may concern:

Be it known that I, OLE O. KITTELESON, a citizen of the United States, residing at Rock Falls, in the county of Whiteside and State 5 of Illinois, have invented certain new and useful Improvements in Wire-Barbing Machines; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 My invention has reference to machines for seating barbs on fence-wires, and has more special reference to certain mechanism for coiling the barb.

20 My machine is intended to operate upon fence-cables consisting of at least two wires or strands, which strands are bent across each other at intervals before being twisted, as shown in Figure 3; and my invention consists of the mechanism, hereinafter described, for coiling 25 the central portion of the barb between such strands and around the point where such strands cross each other, as shown in said Fig. 3.

30 In the upper barb of Fig. 3 the upper point, *x*, of such barb was originally projected between the parallel strands *y y*, directly under and in the same direction in which said point *x* now extends. It was then seized by the coiler, and while certain mechanism bent the 35 strands *y y* past each other in a vertical plane contiguous to the side of such barb, the coiler caused such point *x* to perform a complete circle, in a substantially horizontal plane, around the point of mutual crossing of the strands *y y*. 40 This operation produced a circle at the center of the barb, and left the point *x* projecting in its original direction and with each of the strands *y* above the barb at one side of the coil and below the barb at the other side of such 45 coil, as shown in Fig. 3. The barb was then cut from the main wire at the point *x'*, and the barb was then complete and the strands ready to be twisted in the usual mode.

50 The mechanism which accomplishes the above described seating of the barb I claim as

my invention, and I will now proceed to describe the same.

Fig. 1 is a plan view of a machine embodying my invention. Fig. 2 is a vertical longitudinal section at the side of the strands *y y* in Fig. 1. Fig. 3 exhibits two views of the barb when seated. Fig. 4 is a side elevation of the mechanism involved in rotating the coiler *G* in a horizontal plane and the devices employed to intermittently elevate and depress such coiler.

The mechanism shown in Fig. 4 is placed transversely of the machine about opposite the entrance of the barb *H*.

A is the bed of the machine, on which is 65 transversely journaled the rotating shaft *B*, driven by the pulley *B'*, or in any other suitable way. The strands *y y* are intermittently fed in the usual mode, by means of a pitman, *B''*, attached at its inner end to a crank-wrist, *B'*, on the shaft *B*, and at its outer end to a loose collar, *B'*, carrying a pawl, *B'*, which latter intermittently engages a ratchet, *B'*, fixed on the shaft *C*, which latter carries the feed-pulley *C'*. A short shaft (not shown) is seated 70 on the boxes *C*, directly above and parallel with the shaft *C*, and carries a pulley corresponding to the pulley *C'*, directly over the latter, such supposed shaft being intermittently rotated by a gear which engages with and corresponds to the gear *C* on the shaft *C*, the wires *y y* being held and advanced between such feed-pulleys in the usual way. The barb wire *H'* is intermittently advanced in substantially the mode above described by means of 85 the barb-feed pulley *H'*, seated on the shaft *H''*, journaled lengthwise of the machine and intermittently rotated in the usual way by means of a pitman, *H''*, attached at one end to a crank-wrist, *D'*, on the outer end of the shaft *D*, and 90 at the other end to a loose collar, *H'*, on the outer end of the shaft *H''*, the collar *H'* carrying a pawl, *H'*, which intermittently engages a ratchet, *H'*, fixed on the shaft *H''*. A short shaft (not shown) carrying a gear and feed 95 pulley corresponding to the pulley *H'* and gear *H''*, is placed over the shaft *H''*, so that the barb-wire *H'* is held between and intermittently advanced by the pulley *H'* and its twin pulley, in the usual and well-known mode. 100

The shaft D is rotated by means of a bevel-gear, D', on its inner end, which is engaged and rotated by the contiguous bevel-gear B⁶, on the driving-shaft B.

5 E E are twin guides through small holes v, in the inner ends of which the wires y y, respectively, pass. The guides E E are long bars placed lengthwise of the machine, and are pivoted near their centers to a transverse horizontal stud, E', fixed on the frame A. The outer ends of the guides E E extend, respectively, above and below the shaft B, and are given vertical oscillation in opposite directions by partially annular cams E², formed on 15 opposite sides of the shaft B, which flanges respectively act in the rotation of the shaft B upon friction-rollers E³ on the outer ends of the guides E, causing the inner ends of such guides to pass each other in a vertical arc at 20 each rotation of the shaft B, and the wires y y to cross each other vertically. The rollers E³ are held to the cams E² by coiled springs E⁴.

F is a shaft driven forward by the cam D', located on the shaft D, and confined in way 25 F', formed in the plate J and cap F², attached to the bed A, and is provided at its inner end with the horizontal cross-head F³, which latter is further provided with an inclined recess, F⁴, and wedge-like horizontal stud F⁵. As the 30 shaft F makes its instroke, it forces the stud F⁵ between the strands y y and holds the latter apart and steady for the passage of the wire H' and the end of the coiler between them, and at the same time places the recess F⁴ in 35 position to receive the inner end of the barb H, and slightly raises the latter to position to be caught in the end of the coiler G. After the latter has coiled the barb between the wires y y, the shaft F has instantly its outstroke and 40 withdraws the stud F⁵, so as to permit the subsequent twisting of the strands y and be out of the way of the onward movement of the barb and strands. The recoil or outstroke of the shaft F is caused by the coiled spring F⁶, 45 attached at one end to the bed A and at the other to the cross-head F³.

Referring to Fig. 4, which exhibits the mechanism for actuating the coiler G, J is a vertical plate seated on the bed A, transversely of 50 the machine. In the inner end of the plate J is journaled vertically a short shaft, G', to the lower end of which is rigidly attached the coiler G, the latter being shaped like a cork-screw, and having its lower end slightly concaved to receive the barb H. The upper end 55 of the shaft G' is provided with a pinion, G², which is rotated by a traveling rack, G³, carried in horizontal ways G⁴, formed in the upper end of the plate J. The rack G³ is reciprocated in said ways by means of a bell-crank lever, K, pivoted at its angle K' to the bed A. The outer end of the lever K is provided laterally with a friction-roller, K², which traverses the elongated eccentric groove K³ in the 60 cam K⁴, fixed on the shaft D. The upper end of the lever K is attached to a pitman, L, and the latter attached to the rack G³ by means of

a pin, G⁵, fastened to the back of the rack G³ and extending through a slot, J', in the plate J, parallel with the ways G⁴, which slot J' is 70 traversed by the pin G⁵. Thus the coiler G is given the necessary rotation. It is necessary to intermittently raise the coiler G to permit the point x of the barb H to cross its central portion. This is accomplished by allowing to 75 the shaft G' a sufficient vertical play in its journal-bearing G⁶, and pivotally attaching the upper end of the shaft G' at G⁸ to the inner end of the lever M. The latter is pivoted near its center at M' to the side of the 80 plate J, as indicated in dotted lines in Fig. 4, and the outer end of such lever M rests upon and is actuated by a cam, M', on the shaft D, as shown in dotted lines in Fig. 4, being held to such cam by a coiled spring, M²; or the 85 outer end of the lever M may be provided laterally with a friction-roller adapted to traverse a slotted cam on the shaft D, as does the roller K².

N is the usual fixed shear, and O the usual 90 movable shear, forced over the shear N in the ordinary way by a cam-connection with the shaft B, to sever the barb H after it is seated from the barb-wire H'.

The operation of my invention is as follows: 95 The strands y y and barb-wire H are advanced in the usual way. The shaft F is driven inward, and the stud F⁵ forced between the strands y y, and the wire H' fed forward and its inner end slightly deflected upward in the 100 recess F⁴, and the guides E E simultaneously cross the strands y y close to the wire H at the side of the latter next to such guides. The coiler G is then depressed and given one rotation by the mechanism before described. The 105 end of the coiler G engages the protruding end of the wire H and bends the latter between the strands y y and once around the point of crossing of said strands, as shown in Fig. 3. The coiler G is then instantly uncoiled and 110 slightly raised, the shears N and O sever the barb, the shear O immediately withdraws, and the operation is complete, and the mechanism in place for a repetition.

R and S are the usual pawl and ratchet for 115 regulating the feed of the strands y y.

I have had the machine in operation for several weeks, and it seats an average of one hundred and fifty barbs per minute, and can be driven to seat two hundred per minute. 120

What I claim as my invention, and desire to secure by Letters Patent of the United States, is—

1. The combination of the coiler G, means for elevating and depressing such coiler, and 125 means for causing the point of such coiler to perform a complete circle around the point of intersection of the strands y y, substantially as shown and described, and for the purpose named.

2. The combination of the coiler G, means for rotating and means for elevating and depressing the same, and the shaft F, provided 130 with the stud F⁵, devices for operating the

shaft and the guides E E, and means, shown and described, for operating such guides, substantially as shown and described, and for the purpose described.

5 3. The combination of the coiler G, means for rotating such coiler, shaft F, provided with the stud F⁵ and means for operating it, and guides E E and means for operating them to cross the strands, substantially as shown and 10 described, and for the purpose mentioned.

4. The combination of the coiler G, means for rotating the same, guides E E, shaft F, provided with stud F⁵, and means for operating the guides and the shaft and for intermittently advancing the fence and barb wires, substantially as shown and described, and for the 15 purpose described.

5. In a wire-barbing machine, the combination, substantially as shown and described, of the following elements, to wit: means for intermittently feeding the fence and barb wires, means for separating and holding said fence-wires, means for alternately crossing such wires, the coiler G, adapted to coil the barb around the intersection of the strands, and 20 means for severing such barb when coiled, for the purpose herein named.

In testimony whereof I affix my signature in presence of two witnesses.

OLE O. KITTLESON.
